JOHN HEARL, OF BALTIMORE, MARYLAND, ASSIGNOR TO A. WEISKITTEL & SON COMPANY, OF BALTIMORE, MARYLAND, A CORPORATION OF DELAWARE.

FLUSHING APPARATUS FOR WATER-CLOSETS.

1,153,784.

Specification of Letters Patent. Patented Sept. 14, 1915.

Application filed July 17, 1915. Serial No. 40,400.

To all whom it may concern:

Be it known that I, JOHN HEARL, a citizen of the United States, residing at Baltimore, State of Maryland, have invented certain new and useful Improvements in Flushing Apparatus for Water-Closets, of which the following is a description, reference being had to the accompanying drawing and to the figures of reference marked thereon.

10 The invention relates to new and useful improvements in flushing apparatus for water closets, and more particularly to a flushing device which is frost-proof.

An object of the invention is to provide a 15 device of the above character wherein the supply valve and the flushing valve are independently mounted and controlled by the seat, the flushing valve being disposed so as to operate horizontally.

20 A further object of the invention is to provide a device of the above character wherein the flushing valve is controlled directly by a cam shoulder on the seat and wherein the flushing valve is held by a limiting stop away from the casing when forced 25 open by the water pressure.

A still further object of the invention is to provide a device of the above character with a spring for holding the flushing valve 30 slightly unseated.

In the drawings, which show by way of illustration one embodiment of the invention,—Figure 1 is a view partly in section and partly in side elevation, showing a 35 closet having my improved flushing apparatus applied thereto; Fig. 2 is an enlarged detail in vertical section through the upper valve casing, showing the parts in position for supplying water to the tank; Fig. 3 is 40 a detail showing the flushing valve as unseated by its controlling spring; Fig. 4 is a similar view, showing the valve in full open position resting against the limiting stop.

45 The invention consists broadly in providing a flushing device having a supply controlling valve located below the frost line and a flush controlling valve located substantially at the line of the seat, both of 50 which valves are simultaneously operated by the seat, so that when the supply controlling valve is opened by the depression of the seat the flush controlling valve is closed, so as to direct the water to the air tank, and 55 when the seat is raised so as to allow the

supply valve to close, then the flush controlling valve is opened by the water pressure as it rushes from the tank to the hopper. The water from the supply passes through a pipe connected to the upper valve casing 60 and the valve stem for the valve controlling the supply extends upwardly through this pipe. The spring for depressing the valve is located outside of the pipe, so that no water accumulates in the spring to freeze 65 and render the device inoperative. The flush controlling valve is mounted so as to move horizontally, and is located substantially in the plane of the seat, so that the same may be engaged directly by a cam 70 shoulder on the seat arm. Means is also provided for normally holding the flushing valve slightly off from its seat, and also for limiting the movement of the flushing valve through the action of the water so it is held 75 spaced from the valve casing.

Referring more in detail to the drawings, my improved flushing device is shown applied to a closet having a hopper 1 and a seat 2. The supply pipe is indicated at 3. 80 This supply pipe is connected to the lower valve casing 4 which is located below the frost line. The lower valve casing 4 has a valve seat 5, which is adapted to be engaged by a valve 6. The valve 6 is attached to a 85 valve stem 7 which extends upwardly through a pipe 8 screwed into the lower valve casing 4. The lower valve casing 4 is provided with a by-pass 9, so that when the valve 6 is raised the water from the supply 90 pipe 3 will pass through said by-pass and up around the stem 7 in the pipe 8. The pipe 8 at its upper end is attached to a T-coupling 10. A pipe 11 is suitably connected to this T-coupling at one end, and at 95 its other end is connected to an air pressure tank 12. The water from the supply, when the supply valve is open, rushes into the air tank which is substantially a closed tank, compressing the air therein which expands 100 when the supply valve is closed for forcing the water through the pipe 11 to flush the hopper. This type of closet is well known, and further detailed description of the operation of the tank is not thought necessary. 105

Attached to the hopper spud 13 is an upper valve casing 14. Said upper valve casing 14 is connected to a pipe 15 threaded into the T-coupling 10 by a flanged sleeve 16, co-operating with the flange on the upper end 110

of the pipe 15. This connection permits the T-coupling to be set so that the pipe 11 may be connected thereto directly in rear of the pipe 8, or at one side thereof as the 5 conditions demand. The valve casing is provided with a suitable water-tight packing gland 17, which will be referred to more in detail later. Moving in this packing gland is a coupling sleeve 18, secured to the 10 valve stem. An expansion rod 19 is threaded in the upper end of this coupling sleeve.

An open cage 20 is threaded onto the upper end of the valve casing 14 and this cage 15 serves as an abutment for the spring 21 which holds the valve stem 7 depressed. Said cage at its upper end is threaded to receive a sleeve 22 which is closed at its upper end and formed with square shoulders serving as a means for adjusting the position 20 of said sleeve. The spring 21 extends into this sleeve and bears against its upper closed end. Said spring at its other end bears against a washer 23 which rests on the upper end of the coupling 18. This sleeve 22, 25 as above noted, may be adjusted in the cage and is locked in adjusted position by a lock nut 24. By adjusting the position of the sleeve 22, the pressure of the spring 21 may be varied and thus the pressure of the valve 30 6 against its seat may be adjusted to correspond with the water pressure in the supply main.

The valve casing 14 is formed with a 35 downwardly and outwardly projecting arm 25 which is secured to the hopper spud 13 by a clamping collar 26 of the well known construction. The seat 2 is screwed to a seat iron 27 and this seat iron is formed with forked arms 28 extending each side 40 of the valve casing. A pivot bolt 29 passes through a suitable lug 30 formed on the valve casing and also through the forked arms 28 of the seat iron. This pivot bolt 45 serves as a support for the seat. The extreme outer ends of the arms 28 are curved and also enlarged so as to weight the same. These curved arms engage a cap 31 fixed to the rod 19 which is an extension of the valve 50 stem 7. The cap 31 is secured to this valve rod by a set screw 32 and a lock nut 33. This permits the cap to be adjusted up and down on the rod 19.

The valve casing 14 is formed with a port 55 34 which connects the main part of the valve casing with the arm 25. The outer face of the port 34 is provided with a valve seat 35 and a valve 36 is adapted to engage this valve seat. Said valve 36 is carried by a stem 37 which passes through a suitable 60 stuffing box 38. On the outer end of the valve stem 37 is an adjustable knob 39. This knob is threaded onto the valve stem and is held in adjusted position by a set screw 40. The knob is rounded off and is adapted to 65 be engaged by a cam face 40 on the seat iron

27. A spring 41 may be placed between this knob and the stuffing box. The spring, however, is of sufficient length and tension merely to hold the valve slightly unseated when it is not closed by the depressing of 70 the seat. The valve is moved to open position by the water pressure. A limiting pin 42 is secured to the valve casing in position so that when the valve is forced to open 75 position by the water, it will engage the valve and hold the same spaced away from the casing. This prevents the valve freezing on its seat, and also prevents the valve freezing against the casing.

The packing gland 17 consists of a sleeve 30 43, threaded into the valve casing, a rubber sleeve 44 which rests against a shoulder 45 of the valve casing and projects downwardly below said shoulder, a washer 46 of metal and a suitable packing washer 47. The sleeve 43 forces the packing against the washer and the rubber sleeve against its shoulder, thus forming a water-tight packing gland for the coupling 18, which slides in the same. Said coupling 18 is formed with a projecting flange 48 at its lower end. This flange when the valve stem is raised is adapted to engage the lower end of the rubber sleeve 44 and further insure a water-tight joint at this point in the valve casing, 90 when the valve casing is subjected to the water pressure from the supply, that is, during the filling of the tank.

When the seat 2 is depressed the valve 36 through the action of the cam face 40 on the knob 39 will be forced inwardly, and this will seat the valve and close the port 34. This same movement of the seat causes the arms 28 to engage the cap 31 and raise the valve stem 7, unseating the valve controlling the supply and permitting the water from the supply to pass through the by-pass 9: thence through the pipe 8 and the pipe 11 to the tank 12. The amount of water entering the tank 12 will depend upon the pressure of the water main. When the seat 2 is released the spring 21 will operate to depress the valve stem 7, seating the valve 6 and cutting off the supply. The water from the tank through the action of the expanding air therein unseats the valve 36, which is now released and passing through the hopper spud flushes the hopper. After all the water in the tank has passed into the hopper, the water remaining in the pipe 8 and below the hopper spud will pass through the drain opening 42^a and the pipe 43^a to the hopper waste pipe. The valve stem 7 is provided with a cylindrical valve 44^a which closes the waste opening 42^a when the supply valve is raised, so as to prevent the water from the supply escaping through the drain pipe 43^a. This cylindrical valve 44^a, however, uncovers the waste opening when the supply valve 130 is seated.

It will be noted from the above description, that the valve for controlling the flushing water is unseated by the pressure of the water. This valve is also operated independently of the supply controlling valve, although simultaneously therewith, by the movements of the seat. Said valve is located substantially in the plane of the seat, so that it may be engaged directly by the seat iron, thus reducing to a minimum the number of parts and thereby the efficiency of the apparatus. It will further be noted that the arm 25 of the valve casing which carries the flushing water to the hopper, extends generally in a downward direction from the port 34, so that all the water in the valve casing will drain either through this downwardly projecting arm into the hopper, or downwardly through the vertical part in the valve casing and the pipe 8 to the drain pipe 43^a. It will also be noted that the flushing valve is held slightly away from its seat, which prevents any water from accumulating or being trapped by the valve through an incomplete or improper depressing of the seat, and by the limiting pin or stop which holds the valve away from the casing likewise any liability of water trapping around the valve is prevented.

It is obvious that minor changes in the details of construction and the arrangement of parts may be made, without departing from the spirit of the invention as set forth in the appended claims.

Having thus described my invention, what I claim as new and desire to secure by Letters Patent, is:—

1. A flushing apparatus including in combination, a hopper, an upper valve casing connected to said hopper, a lower valve casing, a pipe connecting said valve casings, a supply valve in said lower valve casing, a stem extending through said pipes for operating said valve, a closed tank for storing the flushing water, means for raising the supply valve when the seat is depressed, a horizontally disposed valve for controlling the flushing water, a valve stem therefor, and means carried by the seat for directly engaging the last named stem for closing the valve carried thereby when the seat is depressed.

2. A flushing apparatus including in combination, a hopper, an upper valve casing connected to said hopper, a lower valve casing, a pipe connecting said valve casings, a supply valve in said lower valve casing, a stem extending through said pipe for operating said valve, a closed tank for storing the flushing water, means for raising the supply valve when the seat is depressed, a horizontally disposed valve for controlling the flushing water, a valve stem therefor, means carried by the seat for directly engaging the last named stem for closing the

valve carried thereby when the seat is depressed, and a spring for normally holding said last named valve unseated, said valve being moved to full open position by the water.

3. A flushing apparatus including in combination, a hopper, an upper valve casing connected to said hopper, a lower valve casing, a pipe connecting said valve casings, a supply valve in said lower valve casing, a stem extending through said pipe for operating said valve, a closed tank for storing the flushing water, means for raising the supply valve when the seat is depressed, a horizontally disposed valve for controlling the flushing water, a valve stem therefor, means carried by the seat for directly engaging the last named stem for closing the valve carried thereby when the seat is depressed, a spring for normally holding said last named valve unseated, said valve being moved to full open position by the water, and a stop pin for holding said valve away from the casing when in full open position.

4. A flushing apparatus including in combination, a hopper, an upper valve casing connected to said hopper, a lower valve casing, a pipe connecting said valve casings, a supply valve in said lower valve casing, a stem extending through said pipe for operating said valve, a closed tank for storing the flushing water, means for raising the supply valve when the seat is depressed, a horizontally disposed valve for controlling the flushing water, a valve stem therefor, means carried by the seat for directly engaging the last named stem for closing the valve carried thereby when the seat is depressed, said last named valve being moved to full open position by the water, and a stop pin for holding the valve away from the casing when in full open position.

5. A flushing apparatus including in combination, a hopper, an upper valve casing connected to the hopper, a lower valve casing, a pipe connecting said valve casings, a supply valve in said lower valve casing, a stem extending through said connecting pipe for operating said supply valve, a spring located outside of said pipe for normally depressing said valve stem, means operated by said seat for raising said valve stem, a closed tank for the flushing water, a flushing valve in said upper valve casing, a stem carrying said flushing valve, said stem being horizontally disposed and said seat having means for directly engaging the stem of said valve for closing the same when the seat is depressed.

6. A flushing apparatus including in combination, a hopper, an upper valve casing connected to said hopper, a lower valve casing, a pipe connecting said valve casings, a supply valve in said lower valve casing, a stem extending through said pipe for op-

- erating said valve, a closed tank for storing the flushing water, means carried by the seat for raising the supply valve when said seat is depressed, a horizontally disposed valve 5 for controlling the flushing water, a valve stem therefor, said seat having a cam shoulder adapted to engage said last named valve stem when the seat is depressed for closing the same.
- 10 7. A flushing apparatus including in combination, a hopper, an upper valve casing connected to said hopper, a lower valve casing, a pipe connecting said valve casings, a supply valve in said lower valve casing, 15 a stem extending through said pipe for operating said valve, a closed tank for storing the flushing water, means carried by the seat for raising the supply valve when said seat is depressed, a horizontally disposed valve 20 for controlling the flushing water, a valve stem therefor, said seat having a cam shoulder adapted to engage said last named valve stem when the seat is depressed for closing the same, said horizontally disposed valve 25 being moved to full open position by the water, and a stop pin for holding the valve away from the casing when in full open position.
8. A flushing apparatus including in combination, a hopper, an upper valve casing connected to said hopper, a lower valve casing, a pipe connecting said valve casings, a supply valve in said lower valve casing, 30 a stem extending through said pipe for operating said valve, a closed tank for storing the flushing water, means for raising the

supply valve when the seat is depressed, a horizontally disposed valve for controlling the flushing water, a valve stem therefor, means carried by the seat for directly engaging the last named stem for closing the valve carried thereby when the seat is depressed, the seat for said horizontally disposed valve being located adjacent the upper end of the valve casing and the passage 40 in said casing from said seat to the hopper extending downwardly, whereby the same will be quickly drained.

9. A flushing apparatus including in combination, a hopper, an upper valve casing 50 connected to said hopper, a lower valve casing, a pipe connecting said valve casings, a supply valve in said lower valve casing, a stem extending through said pipe for operating said valve, a closed tank for storing 55 the flushing water, means carried by the seat for raising the supply valve when said seat is depressed, a horizontally disposed valve for controlling the flushing water, a valve stem therefor, said seat having a cam shoulder 60 adapted to engage said last named valve stem when the seat is depressed for closing the same, said valve stem for the horizontally disposed valve having an adjustable 65 knob on its outer end adapted to engage the cam shoulder on said seat.

In testimony whereof, I affix my signature, in the presence of two witnesses.

JOHN HEARL.
